WEB ROLL CONTROLLING MECHANISM

Stanley C. Freeman, Mount Vernon, N. Y., assignor to R. Hoe & Co., Inc., Bronx, N. Y., a corporation of New York

Application June 11, 1938, Serial No. 213,146

15 Claims. (Cl. 242—75)

This invention relates to web tension controlling mechanism for use with machines operating upon a web that is drawn from a roll, and more particularly to improvements in web tension controlling mechanism adapted for use with machines for printing upon webs of various widths.

It is desirable that the tension of the web being drawn from a roll into a machine, such as a printing machine, be maintained substantially constant and for this purpose many mechanisms have been provided, among which is a web tensioning mechanism wherein a friction device is provided, which is adapted to be pressed against the periphery of the web roll. This friction device may be in the form of a strap, or an endless belt, supported upon a swingable arm or arms. As different lengths of web rolls are used, it is desirable that the strap or belt be adapted to be shifted to dispose it in position in respect to any length roll that may be used, and at either side of the machine.

One object of this invention is to provide an improved web tension controlling mechanism wherein the friction device may be readily and expeditiously adjusted crosswise of the machine to efficiently operate on a web roll centrally located in the machine or on a web roll located near either side of the machine.

Another object of this invention is to provide in a web tension controlling mechanism common means selectively operable to press a friction device against a web roll and to shift the friction device crosswise of the machine.

Still another object is to provide in a web tension controlling mechanism a friction device movable by and with an arm or arms, mounted to swing toward and away from a web roll, and an electric motor to swing the arm or arms and which is also operable to move the arm or arms crosswise of the machine.

A further object is to provide a web tension controlling mechanism of the above form and structure which is actuated to control the tension of a web being drawn from a roll by means of a member movable in accordance with variations in the tension of the web and which includes a friction device and means controlled by said member, and operable to move said friction device in respect to the web roll to control web tension, and is also operable to move the friction device crosswise of the machine.

It is also an object of this invention to provide a web tension controlling mechanism of generally improved construction, whereby the

same will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction, hereinafter described and claimed.

The preferred embodiment of the invention is 10 illustrated in the accompanying drawing, wherein:

Figure 1 is a side view of a web tension controlling mechanism shown associated with parts of a web printing machine;

Figure 2 is a plan view of the same looking in direction of arrow 2 in Figure 1; and

Figure 3 is an enlarged section taken on line 3—3 of Figure 2.

The parts of the web printing machine to which the web tension controlling mechanism of this invention may be applied, include a web roll support 11, which may be a suitably positioned bracket, or an arm of any of the usual roll supporting reels, upon which a web roll 12 is rotatably mounted in position to have its web 13 drawn therefrom. The web 13 is fed over suitable guide rollers 14, 15 and 16, a roller 17 disposed and carried in a loop 18 of the web 13, guide rollers 19 and 21 and then into the machine.

30 The various guide rollers extend between and are journaled in machine frames 22 and 23. The roller 17, carried in the web loop 18 is mounted between the ends of arms 24 and 25 which are secured upon a shaft 26, also extending between the frames 22 and 23. The shaft 26 is biased to rotate by the weight of the roller 17, but a coiled spring 21 acting on one end of the shaft, acts as a partial counterbalance and may be adjusted if desired to vary the effective weight of the roller. A collar 28 having a short arm 29 is secured to the other end of the shaft 26 and a link 31 extends between, and is secured to the arm 29 and a control operating member 32 of an electric motor controlling device 33 containing switches 34 and 35.

45 The switches 34 and 35 are connected with an electric motor 36 to energize it for operation in either direction. The motor is provided with a gear reducer, and an automatic brake within the motor prevents motion of its rotating portion when it is not energized. Sliding movement of the operating member 32 in either direction, will close one of the switches 34 or 35 to cause operation of the motor 36. By this means the motor 36 is under the control of the roller 17, the

movement of which, due to variations in web tension causing variations in the length of the loop 18 will through the arms 24, 25, shaft 26, arm 29, link 31 and member 32 actuate the proper switch 34 or 35 to cause rotation of the motor 36 in the proper direction for correcting the web tension variation as will hereinafter appear. A more detailed description of the structure and operation of the motor controlling switches by a roller disposed in a web loop may be found in Patent No. 2,155,430, granted April 25, 1939.

The motor 36 is drivingly connected to a shaft 37, extending between the frames 22 and 23, in the following manner. A bevel gear 38 rotated by the motor shaft, meshes with a bevel gear 39, freely rotatable upon the shaft 37. The gear 39 is bolted to a spur gear 41, also freely rotatable upon the shaft 37. The hub 42 of a bracket 43 is secured to the end of the shaft 37 adjacent the motor 36 by a key 44, and is releasably connected to the gear 41 by studs 45 and 46. The studs 45 and 46 (see Figure 3) are threaded into the hub 42 and extend into openings 47 formed in the face of the gear 41. By rotating the studs by means of a wrench applied to a head 48 on each stud the slightly tapered end 49 thereof may be removed from its corresponding opening 47 in the gear 41 to disconnect the hub 42 from the gear 41. Such disconnection will also disconnect the motor 36 from the shaft 37.

A pair of arms 51 and 52 are mounted upon and carried by the shaft 37, being suitably secured thereto to rotate therewith and to slide lengthwise thereon. The arms 51 and 52 support a friction device herein shown in the form of an endless belt 53. The upper run of the belt 53 is wrapped about and led over a pulley 54 carried by and disposed between twin brackets 55 held on arms 51 and 52, over a pulley 56 freely rotatable on the shaft 37 between the arms 51 and 52, and over a driven roller 57 extending between the frames 22 and 23. The lower run of the belt 53 leads from the roller over the web roll 12 and to the pulley 54. Swinging of the arms 51 and 52 downward by the motor 36 rotating the shaft 37, will cause the belt 53 to press against the periphery of the roll 12. By repeated operation of the motor 36, the belt 53 will continue such pressure on the web roll as it decreases in diameter while web is being drawn therefrom.

The belt 53 is driven by the roller 57 which in turn is driven in synchronism with the machine through spur gears 58 and 59 and bevel gears 61 and 62 from a shaft 63 connected to an operating part of the machine. Preferably, the speed of the belt 53 is such as to cause a drag upon the web roll 12 when the belt is in contact therewith. A coiled spring 64 is provided to react between the frame 23 and the hub 65 of a bracket 66 secured to the end of the shaft 37 adjacent this frame 23 to counterbalance the arms 51 and 52. To insure equal and uniform movement of the arms 51 and 52 and both brackets 43 and 66, a bar 67 extends from one bracket to the other and passes through a portion 68 extending from each arm 51 and 52 adjacent the shaft 37.

The means for moving the friction member or belt 53 lengthwise of the shaft 37 to dispose it in its most efficient position relatively to the web roll in use, includes a threaded rod 69 journaled at its ends in the brackets 43 and 66. The rod 69 passes through the bracket 43 and has a pinion 71 secured thereto in position to mesh with

the spur gear 41. The rod also passes through the extending portions 68 of the arms 51 and 52 and cooperates with a nut 72 suitably secured in the arm 51 whereby rotation of the rod 69 will move the arms 51 and 52 in unison along the shaft 37, the arms 51 and 52 being tied together by cross bars 73 and 74. When desiring to move the friction member 53 along the shaft 37, the studs 45 and 46 are removed from the openings 47 in the spur gear 41 to disconnect the bracket 43 therefrom and the motor 36 from the shaft 37. The motor 36 may then be operated to rotate the rod 69 through the spur gear 41 and pinion 71, and move the arms 51 and 52 in either direction. In order that the belt 53 may follow the arms while they are being moved, it is preferable to run the machine slowly in order to rotate the roller 57.

A simple electric circuit for operating the motor 36 is shown diagrammatically in Figure 1 and consists of conductors 75 and 76 leading from the switches 34 and 35 respectively to suitable controls in a motor control box 77 to which the motor 36 is connected by conductors 78. The controls in the box 77 are connected to line wires L1 and L2 by conductors 79. For actuating the controls in the box 77 to cause operation of the motor 36 to move the friction member 53, push buttons 81 and 82 may be provided connected to the controls by conductors 83 and 84 respectively.

By the use of the features and principles of this invention, a friction member such as the belt 53 may be actuated to control the tension of the web running from the roll, and the friction member may be readily and rapidly moved into its most efficient operating position when changing size or position of rolls.

It will be understood that the invention may be embodied in other specific forms without departing from the spirit or essential attributes thereof, and it is therefore desired that the present embodiments be considered in all respects as illustrative and not restrictive, and it will be further understood that each and every novel feature and combination present in or possessed by the mechanism herein disclosed forms a part of the invention included in this application.

What I claim is:

1. In mechanism for controlling tension on a web being drawn from a web roll, a member having arms slidable thereon, a friction device carried by the arms, means for rotating the member to press the friction device against the surface of the web roll and to slide the arms along the member.

2. In mechanism for controlling tension on a web being drawn from a web roll, a member extending lengthwise of and over the web roll, a friction device carried by the member for swinging movement toward the web roll and slidable on the member, and means selectively operable to swing and slide said friction device.

3. In web tension controlling mechanism, a web roll engaging member movable to increase and decrease its pressure upon the roll and slidable in a plane substantially parallel with the axis of the roll, and common means to move and slide said member.

4. In web tension controlling mechanism, a web roll engaging member movable to increase and decrease its pressure upon the roll and slidable in a plane substantially parallel with the axis of the roll, an electric motor to maintain the member in engagement with the web roll as web

is drawn therefrom, and means to control said motor.

5. In web tension controlling mechanism, a web roll engaging member movable to increase and decrease its pressure upon the roll and slideable in a plane substantially parallel with the axis of the roll, an electric motor to maintain the member in engagement with the web roll as it decreases in diameter due to web being drawn therefrom, means to control said motor to maintain the member in engagement with the roll, and means to actuate said motor to slide said member.

6. In web tension controlling mechanism, a web roll engaging member movable to increase and decrease its pressure upon the roll and slideable in a plane substantially parallel with the axis of the roll, an electric motor to maintain the member in engagement with the web roll as it decreases in diameter due to web being drawn therefrom, means controlled by the tension of the web drawn from the roll to control said motor to maintain the member in engagement with the roll, and means to actuate said motor to slide said member.

7. In a web tension controlling mechanism, a friction member swingable into engagement with the periphery of a web roll having a web being drawn therefrom and slideable in a plane substantially parallel with the axis of the roll, a rotatable shaft supporting and operably connected to said friction member to swing it, a rotatable threaded rod operably connected to said member to slide it, and common means to rotate said shaft and said rod.

8. In a web tension controlling mechanism, a friction member swingable into engagement with the periphery of a web roll having a web being drawn therefrom and slideable in a plane substantially parallel with the axis of the roll, a rotatable shaft supporting and operably connected to said friction member to swing it, a rotatable threaded rod operably connected to said member to slide it, an electric motor for rotating said shaft and said rod, and means to drivingly connect and disconnect said motor from said shaft.

9. In a web tension controlling mechanism, a friction member swingable into engagement with the periphery of a web roll having a web being drawn therefrom and slideable in a plane substantially parallel with the axis of the roll, a rotatable shaft supporting and operably connected to said friction member to swing it, a rotatable threaded rod operably connected to said member to slide it, an electric motor, a gear driven by said motor, a pinion gear connected to said rod and in mesh with said gear, a hub secured to said shaft, and means to connect and disconnect said hub to said gear.

10. In a web tension controlling mechanism, a friction member swingable into engagement with the periphery of a web roll having a web being

drawn therefrom and slideable in a plane substantially parallel with the axis of the roll, a rotatable shaft supporting and operably connected to said friction member to swing it, a rotatable threaded rod operably connected to said member to slide it, an electric motor for rotating said shaft and said rod, and means responsive to the tension of the web being drawn from said roll to control said motor when it is rotating said shaft.

11. In a web tension controlling mechanism, a friction member swingable into engagement with the periphery of a web roll having a web being drawn therefrom and slideable in a plane substantially parallel with the axis of the roll, a rotatable shaft supporting and operably connected to said friction member to swing it, a rotatable threaded rod operably connected to said member to slide it, an electric motor for rotating said shaft and said rod, means responsive to the tension of the web being drawn from said roll to control said motor when it is rotating said shaft, and means to disconnect said motor from said shaft whereby its operation will rotate said rod.

12. In a web tension controlling mechanism, an endless belt slidably supported on a rotatable shaft and swingable, when said shaft is rotated, into engagement with a web roll, means to slide said belt along said shaft in a direction substantially parallel to the axis of the web roll, driven means over which said belt is wrapped to drive said belt in any of its positions, and common means to rotate said shaft and slide said belt.

13. In mechanism for controlling tension on a web being drawn from a web roll, a member having arms slideable thereon, a friction device carried by the arms and adapted to engage the web roll, a threaded rod operatively engaging said arms, and means to rotate said rod to slide the arms along said member.

14. In a device for controlling tension on a web being drawn from a web roll, a member having arms slideable thereon, a friction device carried by the arms, and means for rotating the member to press the friction device against the surface of the web roll and alternatively for sliding the arms along said member.

15. In a mechanism for controlling tension on a web being drawn from a web roll and fed to a printing machine, a shaft having arms connected thereto, an endless belt supported on a plurality of spaced apart pulleys one of which is carried by the arms and movable therewith parallel to the axis of the shaft, means connected to the machine for driving the belt at a speed slightly below that of the web, and power operated means for swinging the arms toward and away from the roll to vary the pressure of the belt thereon, and for moving the arms parallel to the axis of the shaft to accommodate rolls of various lengths.

STANLEY C. FREEMAN.
